United States Patent Office

Des. 181,765

Patented Dec. 17, 1957

181,765

TELEVISION AND RADIO PROGRAM REMINDER DEVICE

Louis L. Verveer, Downers Grove, Ill.

Application April 10, 1957, Serial No. 45,668

Term of patent 14 years

(Cl. D74—1)

FIG. 1

FIG. 2

FIG. 3

Fig. 1 is a side elevational view of a television and radio program reminder device embodying my new design;

Fig. 2 is a front elevational view of the same as seen from the right hand side in Fig. 1;

Fig. 3 is a top plan view thereof.

I claim:

The ornamental design for a television and radio program reminder device, substantially as shown.
